Primary Examiner — W. A. Teddy Falloway

(57) **CLAIM**

The ornamental design for a tray for packaging rechargeable batteries, as shown and described.

DESCRIPTION

1. Tray for packaging rechargeable batteries
- 1.1 : Perspective view 1 (back, top, right side)
- 1.2 : Perspective view 2 (front, bottom, left side)
- 1.3 : Front
- 1.4 : Back
- 1.5 : Left
- 1.6 : Right
- 1.7 : Top
- 1.8 : Bottom
- 1.9 : Enlarged cross-sectional view taken along line 1.9-1.9 in reproduction 1.3
- 1.10 : Enlarged cross-sectional view taken along line 1.10-1.10 in reproduction 1.3

1 Claim, 10 Drawing Sheets
